UNITED STATES PATENT OFFICE.

WILLIAM CHRISTIAN SCHULZ, OF INDIANAPOLIS, INDIANA.

HAIR-COMB.

No. 861,398.

Specification of Letters Patent.

Patented July 30, 1907.

Application filed January 18, 1907. Serial No. 352,947.

To all whom it may concern:

Be it known that I, WILLIAM CHRISTIAN SCHULZ, a citizen of the United States, residing at Indianapolis, in the county of Marion and State of Indiana, have invented certain new and useful Improvements in Hair-Combs, of which the following is a full, clear, and exact description, reference being had to the accompanying drawings, forming a part hereof.

My invention has relation to improvements in hair combs; and it consists in the novel details of construction more fully set forth in the specification and pointed out in the claims.

In the drawings, Figure 1 is a plan of the completed comb, broken at parts; Fig. 2 is a longitudinal edge view; Fig. 3 is an end view of the male section; Fig. 4 is a plan of the male section; Fig. 5 is a plan of the female section; Fig. 6 is an end view of the female section; and Fig. 7 is a cross section on the line 7—7 of Fig. 1.

20 The object of my invention is to construct a comb of two sections separable from one another so that the teeth of the comb can be cleaned to better advantage, thereby producing a comb which from a sanitary standpoint is unsurpassed.

25 In detail the invention may be described as follows: Referring to the drawings, 1, represents the body portion of what I term the male section of the comb, the same being provided with teeth t , and 2 the female section provided with teeth t' . The opposite ends of the female body portion terminate in inwardly turned flanges or equivalent formations 3 forming grooves or ways with the body proper for the reception of the

body of the male portion. The teeth of the respective portions or sections are so distributed that when the sections are assembled (Fig. 1) the teeth of one section 35 alternate with those of the contiguous section so that they conform in proximity to those of an ordinary comb. The bases of the teeth t' curve inwardly toward the body 2 forming a series of offsets or ledges 40 on which the lower edge of the body 1 rests, this arrangement serving to bring the teeth of the assembled sections virtually in the same plane (Fig. 7). It will be seen that the male section is readily insertible into the female section and as readily separable therefrom, and that by taking the sections apart, the teeth are 45 readily accessible and hence permit of perfect cleaning. When the parts are assembled one set of teeth become the complement of the adjacent set, thus making a perfect comb.

Having described my invention what I claim is: 50

A comb comprising a male section having a toothed body portion, a female section having a toothed body portion, terminal grooves or ways on the female section for receiving the body of the male section, offsets forming collectively a ledge, connecting the bases of the teeth of the 55 female section to the body thereof, the toothed edge of the male section resting on and positively supported by said ledge, whereby the teeth of the respective sections are brought into the same plane, the teeth of one section alternating with those of the adjacent section, substantially as 60 set forth.

In testimony whereof I affix my signature, in presence of two witnesses.

WILLIAM CHRISTIAN SCHULZ.
